[57] CLAIM

The ornamental design for a lighter or the like, as
shown and described.

DESCRIPTION

FIG. 1 is a front elevational view of a lighter or the like,
showing my new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof; and

FIG. 7 is a top and left front perspective view thereof,
with a button depressed to strike the lighter or the like.
